UNITED STATES PATENT OFFICE

166,981

MOTION-PICTURE PROJECTOR

Frederick G. Knowles, Rochester, N. Y., assignor
to Eastman Kodak Company, Rochester, N. Y.,
a corporation of New Jersey

Application February 21, 1952, Serial No. 18,627

Term of patent 7 years

(Cl. D61—1)

To all whom it may concern:

Be it known that I, Frederick G. Knowles, a citizen of the United States of America, residing in Rochester, in the county of Monroe and State of New York, have invented a new, original, and ornamental Design for Motion-Picture Projector, of which the following is a specification, reference being had to the accompanying drawings, forming a part thereof.

This application is a continuation-in-part of my application Ser. No. 16,638 for Motion-Picture Projector, filed September 14, 1951.

In the drawings:

Fig. 1 is a perspective view of a motion-picture projector showing my new design; and

Fig. 2 is a top plan view of the projector shown in Fig. 1.

The dominant feature of my design resides in those portions shown in full lines.

I claim:

The ornamental design for a motion-picture projector, as shown and described.

FREDERICK G. KNOWLES.
